ARTICLE HOLDER

William V. Johnson, Washington, D. C.

Application October 26, 1940, Serial No. 363,038

4 Claims. (Cl. 24—3)

This invention relates to an article holder and has relation more particularly to a device of this character especially designed and adapted for use in the holding of pipes and other articles for personal use.

It is an object of the invention to provide a device of this kind which can be readily engaged with an article of clothing, such as a belt, the waist band of a nether garment, etc.

It is also an object of the invention to provide a device of this kind comprising a plurality of hingedly connected plates normally urged into clamping action and wherein said plates may be expanded or extended upon pressure to permit an article to be applied thereto or removed therefrom.

The invention consists in the details of construction and in the combination and arrangement of the several parts of my improved article holder whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawing, wherein:

Figure 1 is a view in elevation of an article holder constructed in accordance with an embodiment of my invention and applied to a belt, said belt being in fragment and the device being also illustrated in holding engagement with a pipe;

Figure 2 is a sectional view taken substantially on the line 2—2 of Figure 1;

Figure 3 is a view in end elevation of the device as herein disclosed;

Figure 4 is a sectional view taken substantially on the line 4—4 of Figure 3;

Figure 5 is a sectional view taken substantially on the line 5—5 of Figure 3.

As herein embodied my improved article holder comprises two substantially duplicate articulated sections S, each of said sections comprising two plates 1 and 2 substantially of the same dimensions and being of considerable width but herein disclosed as of a width in excess of the length. Adjacent end portions of the plates 1 and 2 of each section S are formed to provide the interfitting and inwardly disposed knuckles 3 through which are directed the pintles 4 where-

by the plates 1 and 2 are connected for relative swinging movement.

The outer ends of the plates 1 and 2 of one section S are formed at the immediate side portions thereof with the inwardly disposed knuckles 5 and in close contact with the inner ends of these knuckles 5 are the inwardly disposed knuckles 6 carried by the outer ends of the plates 1 and 2 of the second section S. These knuckles 6 are spaced apart a material distance and disposed through the knuckles 5 and 6 at one end of the device is a pintle 7 for pivotally connecting said end portions of the sections S while disposed through the knuckles 5 and 6 at the opposite or upper end of the device is a pintle 8 whereby said end portions of the sections are also pivotally connected.

The pintles 7 and 8 between the knuckles 5 are surrounded by the coil springs 9 of predetermined tension. One extremity of each of the springs 9 is provided with an extension 10 contacting from without with the adjacent portion of the plate 1 or 2 of one of the sections and having at its opposite end an extension 11 contacting with the adjacent portion of the plate 1 or 2 of the second section. These springs 9 are of a tension sufficient to normally maintain the plates 1 and 2 in compacted or folded relation and under a tension sufficiently to effectively hold an article inserted between the sections S, as for example the stem of a pipe P as particularly illustrated in Figures 1 and 2 of the drawing.

By pressing upon the ends of the device, as by a squeezing action of a hand, the device may be caused to expand sufficiently to facilitate the insertion within or the removal therefrom of the stem of the pipe P or other desired article.

The side margins of the plates 1 and 2 are provided with the inwardly disposed flanges 12 extending substantially entirely along said margins and which flanges provide means for maintaining between the sections S the tubular gripping member M, the walls of which are flexible.

When the holder is in its normally compacted or closed adjustment, as effected and maintained by the springs 9 as illustrated in Figure 3, this member M substantially entirely overlies the opposed faces of the plates 1 and 2 of the sections S with the intermediate knuckles 3 contacting the intermediate portion of said member M. The folds of the member M and the radii of the knuckles 3 are such to prevent the intermediate pivotal connection between the plates 1 and 2 of the sections S passing inwardly beyond dead center so that upon pressure on the outer

end of the device the pivotally connected inner ends of the plates 1 and 2 will swing outwardly and for a distance sufficient to permit the ready insertion through the member M of the article to be held or to allow the removal of such article.

The flanges 12 are not required at both ends of all of the plates 1 and 2 but said flanges 12 may be in staggered relation as illustrated in the drawing.

The pindle 8 is of a length to extend a slight distance beyond the adjacent sides of the assembled sections S and has its extremities continued by the outwardly and substantially perpendicularly related short arms 14. These arms 14 have their outer ends continued by the elongated arms 15. These arms 14 and 15 are in substantially right angular relation and the outer end portions of the arms 15 are connected by a cross arm 16. The arms 14 are of such length as to permit the ready insertion of the arms 15 rearwardly of a belt B, the waist band of a nether garment, or other article of clothing worn by a person, and with the sections S overlying the outer ends of the belt B or the like as particularly illustrated in Figures 1 and 2. As illustrated in the drawing, the arms 15 are to be inserted from above behind the belt B or the like to facilitate the maintenance of the holder in place.

With the device applied to a belt or the like, it is believed to be obvious that the sections S with or without an article therethrough may be readily swung upwardly about the pindle 8 to facilitate the application or removal of the article, such as the pipe P. It is also believed to be apparent that after the application or removal of the article from the holder the holder proper as comprised in the sections S will swing downwardly by gravity to lie close against the belt B or the like.

From the foregoing description it is thought to be obvious that an article holder constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as herein-after claimed.

I claim:

1. An article holder comprising two overlying sections, each of said sections comprising two flat plates, means for pivotally connecting the adjacent inner end portions of the plates, means for pivotally connecting the outer end portions of the plates of one section with the outer end portions of the plates of the second section, and means for constantly urging the plates of one section toward the plates of the second section.

2. An article holder comprising two overlying sections, each of said sections comprising two flat plates, means for pivotally connecting the adjacent inner end portions of the plates, means for pivotally connecting the outer end portions of the plates of one section with the outer end portions of the plates of the second section, means for constantly urging the plates of one section toward the plates of the second section, and a flexible tubular gripping member interposed between the sections and substantially overlying the opposed faces of the plates.

3. An article holder comprising two overlying sections, each of said sections comprising two flat plates, means for pivotally connecting the adjacent inner end portions of the plates, means for pivotally connecting the outer end portions of the plates of one section with the outer end portions of the plates of the second section, means for constantly urging the plates of one section toward the plates of the second section, a flexible tubular gripping member interposed between the sections and substantially overlying the opposed faces of the plates, and means for holding the gripping member between the sections.

4. An article holder comprising two overlying sections, one of said sections comprising two flat plates, means for pivotally connecting the adjacent inner end portions of the plates, means for pivotally connecting the outer end portions of the plates of one section with the outer end portions of the plates of the second section, said pindle extending beyond opposite sides of the sections, angularly disposed short arms carried by the extended portions of such pindle, and substantially perpendicularly related elongated arms at the outer end portions of the short arms, said arms providing means for engaging the device with a support.

WILLIAM V. JOHNSON.
